UNITED STATES PATENT OFFICE.

FRANK CHASE, OF BOSTON, MASSACHUSETTS, ASSIGNOR TO CHARLES F. JOHNSON, OF SAME PLACE.

MACHINE FOR LASTING BOOTS OR SHOES.

SPECIFICATION forming part of Letters Patent No. 319,784, dated June 9, 1885.

Application filed March 11, 1885. (No model.)

To all whom it may concern:

Be it known that I, FRANK CHASE, of Boston, in the State of Massachusetts, have invented a certain new and Improved Machine for Lasting Boots and Shoes, of which the following is a specification.

My invention relates, mainly, to means whereby several or all of the parts which hold and stretch the upper and force its edges over upon the bottom of the last into proper position to receive the outer sole may be simultaneously actuated by a single power mechanism, and still have independency of movement, which enables them to automatically conform to the shape of the last upon which they operate. These parts, which immediately hold and stretch the upper, I term "wipers."

According to my invention the degree of movement of the individual wipers to stretch the upper is made dependent, not upon their adjustment relative to the power mechanism, to be varied by the workman for every different shape of last, but upon the shape of the last itself and the elasticity of the upper. I am thus enabled to last shoes of different sizes, and either rights or lefts, without specially adjusting the machine, and to stretch the upper to a uniform tension.

My invention also relates to the clamping devices which hold the last in place.

In order to clearly describe my invention, I have shown in the accompanying drawings a method of carrying it into effect.

In the drawings, Figure 1 is a plan view of a lasting machine embodying my invention. Fig. 2 is a vertical section of a portion of the same on line 2 2 of Fig. 1. Fig. 3 is a longitudinal vertical section on line 3 3 of Fig. 1. Fig. 4 is a transverse vertical section on line 4 4 of Fig. 1. Fig. 5 is a plan view enlarged of devices which clamp the heel and last the upper at that point. Fig. 6 is a similar view of devices which operate upon the toe. Fig. 7 is a plan view of the guides which support and direct the toe-clamping devices. Fig. 8 is a bottom plan view of the toe-clamp.

A is a standard supporting a table-like frame, A', having a central opening, around which are arranged the clamping and lasting devices.

A post, B, projects into the opening from below to serve as a vertical support for the last. It is jointed at b b to permit the last to take its proper position as the clamping devices advance upon it.

Various forms of clamps for holding the last in position may be used with the automatic wipers hereinafter described; but I prefer the forms shown.

In the construction illustrated the last is to be held between a two-part heel-clamp, H H, and a toe-clamp, T T, also made in two parts. Their grasping-faces are provided with cushions h t, of rubber or other suitable material, to prevent injury to the upper and hold the last more firmly. The clamps H and T slide in suitable ways, a, (see Fig. 7,) upon the frame A', and are actuated by right-and-left screws H' T', engaging with nuts h' t', which latter are seated in recesses in the clamps.

The screws H' T' may be actuated from a single hand-wheel, C, through the medium of gear-wheels c and shafts c' c'. Two shafts are used, one upon each side of the lasting-opening, for a purpose to be described.

In order to more securely hold the last and to fit the narrower heels and toes of shorter lasts, the two parts of each clamp are arranged to approach one another laterally as they advance. This is effected by making the ways a, upon which the two-part clamps slide, nearer together at their inner than at their outer ends, as shown in Fig. 7. The parts of the clamps H T are provided with correspondingly-inclined ways d', which are kept in engagement with the ways a by springs d' d' d''. The latter are arranged between the two parts of the clamps and serve to separate said parts as they are withdrawn by screws H' T'.

To compensate for the decreased vertical thickness at the toe of shorter lasts, I prefer to arrange the toe-clamp to rise as it advances. This may be effected by constructing each of the parts T with a supplemental portion, T'', vertically movable relative to part T, but carried thereby longitudinally, as by means of a projection, t''.

The frame A' is also formed with an inclined plane, D, of a suitable angle, upon which the parts T'' T'' rest, and by which they are

forced upward to meet the last as the toe-clamp advances. In this case the cushions *t* will be carried by the parts *T*" *T*'. The spring *d*" serves to keep these parts properly separated 5 and in their seats in the main portions *T*.

The heel and toe clamps are each provided with wipers to assist in holding the work and to last the upper at those points.

E is a horizontal slide arranged to move in 10 suitable ways, *e*, formed in the top of the heel-clamp, at the middle thereof. It is held in a central position between the parts *H* *H* by means of springs *g*, seated in the said parts and bearing against the sides of a downward-extending portion, *e*', of the slide. Its inward 15 end is suitably formed to engage with the upper and act as a wiper to stretch and last it over upon the sole.

F *F* are slides situated upon each side of 20 slide *E* and arranged to operate at an angle thereto, their ends also being formed to act as wipers. By giving these slides and their guiding-ways the forms of arcs of circles concave toward one another, they will very effectively operate as they move inward on their 25 respective curves to gather in and crimp together the fullness of the upper at the heel. The slides *F* *F* are each provided with pulleys *f*, and are connected with the slide *E* by means 30 of links *i*. Cords or chains *L* *L*, passing around the pulleys *f*, are conducted by suitable guide-pulleys, *l*, to the power mechanism, whereby the cords may be wound up and the slides *E* *F* *F* caused to advance in their respective 35 paths. The slides are normally held retracted by springs *G* in an obvious manner. The ways or guides for the slides may be formed, as shown, by suitably recessing the parts *H* *H* and providing them with covering-plates *I*. 40 I prefer to allow the slides to yield upward at their inner ends, that they may more effectually conform to the last. This I effect by recessing the covering-plates *I* and interposing between them and the slides springs of the necessary 45 stiffness. Such a spring is shown at *I*' as applied to the slide *E*.

The toe-clamp is provided with slides *F*' *F*', pulleys *f*, cords *L* *L*, and springs *G* *G*, of similar construction and operation to the analogous parts just described in connection with the heel-clamp. For the toe, however, I prefer to use somewhat different lasting devices. The part *E*' does not slide in the toe-clamp, but carries two pivoted arms, *J*, adapted to act 55 as wipers, and provided with slots *j*, in which work pins carried by the curved slides *F*' *F*'. As these slides are drawn inward by the cords, the arms *J* are swept around and gather in and effectively last over the fullness of the toe- 60 portion of the upper. In connection with the toe-clamp I may use a spring-actuated lever, *K*, pivoted at *k* to the part *E*'. The edge of the upper may be inserted between the inner ends of said lever and part *E*' and there held by 65 the action of the spring *K*' beneath the outer end of the lever. A tension-screw, *K*'', serves to regulate the strength of the spring. By

these devices the upper may be more effectively stretched along the instep and front of the shoe.

To insure that the upper conforms closely to the hollow portion of the last between the instep and the toe, I employ a convex two-part presser, *M*, carried by springs *M*', preferably attached to the two parts of the toe-clamp. These pressers can yield downward and laterally or outward as the last is clamped, thus drawing the upper toward each side in opposite directions, as well as pressing it against the last, thus causing it to conform 80 closely to the top of the latter.

I will now describe the devices which, when the work has been securely clamped and operated upon by the devices already described, act to last the upper along the sides.

N are ways formed on the frame *A*' at each side of the lasting-opening, and in proximity to and parallel with the shafts *c*' *c*', already mentioned. To these ways are fitted longitudinal slides *O*, engaging, through the medium of half-nuts *O*', held in the slides by screws *o*, with screw-threads upon the shafts *c*'. (See Fig. 2.) I have shown six of the slides upon each side of the lasting-opening. A description of those upon one side will suffice for both. 95 One of the slides, near the middle of the series, is provided with a half-bearing, *O*", instead of a half-nut, and the shaft is correspondingly cut down, as shown at *c*'. On one side of this slide, which, obviously, as the shaft revolves, remains stationary, the shaft *c*' is provided with right-hand screw threads, 1, 2, and 3, and upon the other side with left-hand threads, 4 and 5, which threads engage with the half-nuts mentioned. The threads 100 are also of different pitch, threads 2 and 5 being twice the pitch of 3 and 4, and thread 1 being three times the pitch. The result of this arrangement is that as the shaft *c*' is turned in one direction or the other the distances between the slides *O* are all uniformly increased or diminished. These slides are properly arranged at the sides of the lasting-opening and between the heel and toe clamps, and as the screws *H*' *T*' are geared with shafts 115 *c*' *c*' a uniform arrangement relative to the clamps will be preserved at all times as the clamps advance or retreat, though greater or less spaces between the slides will adapt them to lasts of different lengths.

P represents blocks pivoted to slides *O* at *p* and supporting in suitable ways transverse slides *R*, which latter carry at their inward ends the wipers *W*. The wipers are preferably mounted upon pivots *w*, (see Fig. 4,) which are horizontal and transverse to the last, so that they may oscillate in planes parallel with the last and conform automatically to the contour of the bottom thereof.

The wipers are advanced by cords or chains 130 *L* *L*, which pass from winding-drums *L*' *L*' over suitable guide-pulleys and alternately around the outer sides of a series of pulleys, *r*, carried by the slides *R*, and around the inner

sides of a series of pulleys, p' , carried by the blocks P, and thence over guide-pulleys back to the winding-drums L' L'. The drums are carried by a shaft, Q, which may be actuated by a hand or belt wheel, Q', or equivalent means, either directly or through the medium of a counter-shaft, S, and gearing S', as shown, by which latter arrangement greater power may be applied. Preferably the same cords which 5 advance the side wipers, W, are passed around the pulleys F, as shown. As the drums L' L', therefore, take up the cords L L the two series of pulleys p' and r are drawn together and, the series p' being stationary, the series r and 10 the slides R, with their wipers, are forced inward. The heel and toe slides or wipers F F' F' are simultaneously forced inward by the same cords, the former carrying with them, by means of the links i i , the slide E and the 15 slides F' F', carrying with them the arms J J, as has been explained.

The retraction of the side wipers may be effected by springs, as in the case of the slides F F'; but I prefer and have shown a system of 20 cords, U U, and pulleys r' u . The pulleys r' are arranged in a series upon the slides R, and the pulleys u in a corresponding series upon suitable brackets or extensions, U' U', of the frame A'. Drums U" U" upon the shaft Q serve 25 to take up the cords U U when said shaft is turned backward, the drums L' L' by the same motion giving off the cords L L. The wipers are therefore balanced or held positively between the advancing set of cords and pulleys and the 30 retracting set. More friction is encountered in actuating those of the slides R which are near the middle of the series than in moving those at the ends, due to the greater number of pulleys around which the operating-cords L are 35 obliged to pass to reach the former slides. As a result the end slides of the series R will be brought up to the last before the others. This is not ordinarily objectionable; but in order that the slides may be caused to advance together I have provided them with friction devices whereby those near the ends, which advance more readily, may be retarded. The 40 devices consist of plates s, (see Fig. 4,) which may be forced against the blocks P by setting screws s', engaging with the slides R and bearing against the plates s.

By an inspection of Fig. 4 it will be seen that one of the cords L L and drums L' L' operate to last one side of the shoe, and the other 45 cord and drum the other side. Where one side of the last is more concave than the other, which is generally the case, as with rights and lefts, or the upper at one side is more elastic than at the other, it is necessary for the wipers 50 upon that side to advance farther than those upon the opposite side. I have therefore devised means by which the lasting mechanisms of the two sides of the shoe may operate independently of one another, and by which one 55 of said mechanisms may come to rest while that upon the opposite side of the shoe may 60 continue in operation and advance farther

without special previous adjustment of the machine. I accomplish this, preferably, by giving each of the drums L' L' a yielding connection with their common shaft Q, which enables one of them and the wipers which it actuates to be retarded or to come to rest, while the other drum and its wipers may continue to operate. These yielding connections are 70 formed by two spiral springs, V V, each of which is secured at one end to one of the drums and at the other end to the shaft Q, through the medium of a sleeve, V', secured to the shaft by a screw, v. A slight tension is given 75 to the springs, and the drums are then held against their action by pins l'', inserted in the drums in the paths of arms v' of the sleeve. The cords L L are passed around the drums in a direction to act against the springs. When 80 shaft Q is turned and the wipers advanced and the resistance of the upper to the wipers upon either side of the shoe becomes greater than the force of that one of the springs V through which said wipers are actuated, the 85 spring will yield till its tension becomes sufficient to overcome the resistance of the upper, and properly stretch and last it. In the meantime the shaft Q continues its revolution, and the other spring V independently actuates the 90 wipers and effects the lasting upon the other side of the shoe. Thus the springs V V yield 95 relative to one another, according to the shape of the last and the elasticity of the upper upon the two sides of the shoe, till the lasting of 100 both sides is properly effected.

Shields or guards X, carried by supports x, serve to retain the cords L and U upon their drums, the latter being grooved, as shown. Guards may be provided with all of the pulleys to retain the cords in place, if found desirable.

The engagement of the wipers W with the edges of the upper may be effected in various ways. I prefer, however, a positive rather 110 than a frictional hold, and since the wipers which I employ adjust themselves automatically to the last and to the resistance of the upper it is not necessary for the wipers to have a yielding or frictional engagement with the 115 upper. The wipers are made smooth and rounded upon their under surfaces, and are beveled across their inner faces to correspond approximately with the form of the opposing portions of the last. (See Figs. 4 and 1.) They 120 are provided with sharp hooks or points w', extending upward from their upper faces. When the edge of the upper is turned upward and outward over the inner ends of the wipers and forced down slightly upon the 125 points w', it will be held securely and may be lasted smoothly to any desired tension. Upon 130 releasing the pressure upon the wipers they become individually movable, and a small backward movement of each wiper will ordinarily leave sufficient slack in the edge of the upper between the points where it is secured to the last and to the wiper to permit it to be readily unhooked from the points w'.

Other holding devices may be used with my automatically acting and yielding wipers, in place of the points w' , such as nippers.

Holes w'' are provided in the wipers, through which tacks may be driven to retain the upper in the lasted position.

To facilitate hooking the upper upon the points w' , the wipers are made vertically adjustable by a single and convenient movement z of the workman. In this action, also, the wipers are arranged to automatically conform to the shape of the bottom of the last, so that each wiper will descend individually the necessary distance to reach that portion of the last above which it is situated. The blocks P have been described as pivoted at p to the slides O . These pivot, which may be common to all of the blocks, is at their outer ends, and beneath their inner ends, and resting on the slides O , are arranged a series of springs, q , in suitable seats. (See Fig. 4.) These springs tend to maintain the inner ends of the blocks P , slides R , and wipers W at a height somewhat above the normal position of the sole of the last.

Y Y are horizontal bars arranged at the side of and somewhat below the lasting-opening, and adapted to reciprocate vertically upon bolts z' . Each of these bars is provided with a series of pulleys, y , and a corresponding series of pulleys, y' , is mounted on the inner faces of the blocks P . A single cord, Z , connects the series y with the series y' . (See Fig. 3.) The bars Y Y are each loosely connected at the middle, as by a link, with the end of a transverse equalizing-bar, Y' , (see Fig. 4,) to the middle of which latter is pivoted a vertical rod, Y^2 . The rod Y^2 is operated to draw down the bars Y Y Y by a lever, y'' , having a foot-treadle, z . By this mechanism the wipers W may, by the foot of the workman, be drawn down upon the bottom of the last to receive the upper, the wipers of the two sides moving independently by virtue of the equalizing-bar Y' , and the individual wipers having an independent though simultaneous movement through the system of cords and pulleys Z y y' .

As soon as the upper is in place upon the points w' and the treadle z allowed to rise the two series of springs q will force up the blocks P , slides R , and wipers W . It will be noted that this action very efficiently draws up and stretches the upper over the instep and other portions of the top and sides of the last before its capability for being so stretched is impaired by the friction resulting from folding its edge over upon the bottom of the last.

The general operation of my invention is as follows: The last, either a right or left, or of any ordinary size, with an inner sole and upper applied thereto in the usual way, is fitted upon the post B . By means of the hand-wheel C the heel and toe clamps are caused to advance and secure the work in position. The side wipers are depressed by the treadle z , and the edge of the upper hooked

upon the points w' . The treadle is released and the side wipers permitted to be forced up by the springs q , stretching and drawing the upper snugly up against the last. The side wipers and heel and toe wipers are then forced inward by means of wheel Q' , shaft Q , drums L , cords L , and pulleys p' and r , the individual wipers conforming automatically to the form of the last and the varying elasticity of the different portions of the upper, until the latter is drawn over and fitted to the last at a uniform and proper tension, when it is secured by tacks or otherwise. The wipers are then easily disengaged from the upper and retracted by a reverse rotation of the wheel Q' , through the medium of shaft Q , drums U'' , cords U , and pulleys $r' u$. The heel and toe clamps are withdrawn by reversing the hand-wheel C and the lasted shoe taken from the post B .

I claim as my invention—

1. In a lasting-machine, the combination of a longitudinally-movable sectional clamp for one end of the last, with mechanism, substantially as described, whereby said clamp by and during its longitudinal movement is caused to simultaneously rise and contract or descend and expand, according to the direction of said movement, substantially as and for the purposes hereinbefore set forth.

2. The combination, with the toe-clamp and the lasting devices, of the two-part convex presser M and its vertically and laterally yielding supports, as and for the purposes described.

3. The combination, with the clamp for one of the ends of the last, of lasting and crimping devices adapted to move in circular converging paths in the plane of the bottom of the last for gathering in the fullness of the upper at the end of the last, the side wipers and yielding connections, substantially as described, for actuating said devices in conjunction with but independently of the side wipers, substantially as described.

4. The combination, with the clamp for one of the ends of the last, of the pivoted lasting and crimping arms J , arranged in the plane of the bottom of the last, the side wipers, and yielding devices, substantially as described, for oscillating the arms in said plane to gather and last the fullness of the upper at the end of the last in conjunction with but independently of the side wipers, substantially as set forth.

5. The combination of the wipers and their independent supports pivoted at p , and the equalizing and yielding connections attached to said supports for drawing down the wipers to various distances to automatically conform to the bottom of the last and engage with the upper, substantially as set forth.

6. The combination of the wipers and their independent supports pivoted at p , the equalizing and yielding connections attached to said supports for drawing down the wipers to engage with the upper, and means, substantially as described—as the springs q —for

elevating the wipers and stretching the upper, as set forth.

7. The combination of the wipers and their supports pivoted at *p*, holding devices carried by the wipers for engaging with the upper, and means, substantially as described—
5 as the springs *q*—for elevating the wipers and stretching the upper vertically, as set forth.

8. The combination of lasting devices or
10 wipers independently movable relative to one another, a power-wheel or equivalent device common to several of said wipers, and the yielding devices, substantially as described, for transmitting power from the wheel to the
15 wipers, whereby the latter may be caused by said wheel to advance upon the last and automatically conform to the same and to the varying elasticity of the upper without previous adjustment, substantially as set forth.

20 9. The combination, with the two series of wipers for the two sides of the last, of the devices, substantially as described, for actuating each series independently of the other series, a power mechanism, and yielding connections between said power mechanism and
25 the said actuating devices, whereby the two

series of wipers may be actuated from a single power mechanism and may still operate independently of one another upon the two sides of the last, substantially as set forth. 30

10. The combination, with the sliding wipers and the cords and pulleys for actuating them, of the adjustable friction devices for retarding those of the wipers that offer less resistance to the cord, substantially as described. 35

11. The lasting devices or wipers higher than the bottom of the last and constructed and arranged to be moved over upon the same, said wipers being provided with the sharp projections or hooks *w*, arranged to point away 40 from the last, and mechanism for actuating the wipers, whereby the upper may be forced over upon the bottom of the last, and there held by the said points while being secured, substantially as and for the purposes described. 45

In testimony whereof I have hereunto set my hand.

FRANK CHASE.
